UNITED STATES PATENT OFFICE.

JACQUES BERNARDAUD, OF LIMOGES, FRANCE.

DESIGN FOR A COVERED DISH.

Application filed June 27, 1928. Serial No. 27,298. Term of patent 3½ years.

To all whom it may concern:

Be it known that I, JACQUES BERNARDAUD, a citizen of France, residing in Limoges, in the Province of Haute Vienne, in the Republic of France, have invented a new, original, and ornamental Design for a Covered Dish, of which the following is a specification, reference being had to the accompanying drawing, forming a part thereof.

The figure is a perspective view of the dish, showing my design.

I claim:

The ornamental design for a covered dish as shown.

JACQUES BERNARDAUD.
